DESIGN FOR A SPEEDOMETER

Claude M. Gunn, Kansas City, Mo.

Application September 29, 1937, Serial No. 71,858

Term of patent 3½ years

To all whom it may concern:

Be it known that I, Claude M. Gunn, residing at Kansas City, in the county of Jackson and State of Missouri, have invented a new, original, and ornamental Design for a Speedometer, of which the following is a specification, reference being had to the accompanying drawing, forming part thereof, in which

Figure 1 is a perspective view of a speedometer showing my new design.

Figure 2 is a front elevation of the speedometer shown in Figure 1.

Figure 3 is a side elevation of the speedometer shown in Figure 1.

I claim:

The ornamental design for a speedometer, substantially as shown.

CLAUDE M. GUNN.
